ABSTRACT OF THE DISCLOSURE

A device for aiding in the eructation of babies which comprises a molded body being both transversely and longitudinally arcuated for accommodating the chest and abdominal zones of the baby being assisted and having at one end a chin support extension, there being a tapered portion at the other end for extension into the upper, inter-leg zone,

BACKGROUND OF THE INVENTION

After feeding babies of tender age liquid, such as milk or water, it is requisite that any entrained air be discharged so as to avoid discomfort. The commonly accepted manner of assisting babies to be relieved of any air swallowed during the drinking process is to hold the baby substantially upright with a support against its chest and stomach, as by presentation against the shoulder of the attendant, or more commonly by disposition against one out-stretched hand of the attendant, and then to gently pat the baby's back so as to promote upward flow of such air. It is important that the baby's head be properly supported during this procedure in view of the undeveloped character of the neck vertebra and neck muscles so that no inadvertent injury is caused by jarring developing from the back patting. Thus, the efficacy of effecting this procedure depends substantially upon certain physical characteristics of the attendant so that if the attendant or the mother, as the case may be, has a relatively small hand then obviously proper support may not be provided thereby for the child's stomach and chest area during the air relieving step and with also an obvious lack of appropriate support for the child's head. Also, conversely, a child may be of such proportion that despite the relative hand size of the attendant, inadequate support would result. Accordingly, the present invention seeks to provide a reliable and positive support for a baby to assure effective eructation without respect to any relative physical characteristics of the baby and the attendant.

SUMMARY OF THE INVENTION

It is a primary object of the present invention to provide a device for aiding in the eructation of babies which provides proper support for the stomach and chest of the baby, as well as for the head during the air-relieving operation so that there is obviated any concern as to whether the attendant is physically capable of providing the proper resistance for the supported areas.

It is another object of the present invention to provide a device of the character stated which may be most economically manufactured as from molded plastic, being adapted for high volume production, and with the so-fabricated device being sturdy and resistant to rupture or breakage so as to have longevity of usage.

It is a further object of the present invention to provide a device of the character stated which assures of effective discharge of any entrained air; which is easily utilized; which is light in weight and which presents a uniform support throughout the entire front body portion of the baby.

2

BRIEF DESCRIPTION OF THE DRAWING

FIGURE 1 is a side view of a device for aiding in the eructation of babies constructed in accordance with and embodying the present invention illustrating the device in operative position with a baby.

FIGURE 2 is a top plan view of the inner face of the device illustrated in FIGURE 1.

FIGURE 3 is a side elevational view.

FIGURE 4 is an end view of the chin-adjacent end of the device.

FIGURE 5 is an end view of the end of the device opposite from that shown in FIGURE 4.

FIGURE 6 is a transverse sectional view taken on the line 6—6 of FIGURE 2.

DESCRIPTION OF THE PREFERRED EMBODIMENT

Referring now by reference characters to the drawing which illustrates the preferred embodiment of the present invention, A generally designates a device for aiding in eructation of babies comprising a unitary body portion 1 which may be economically fabricated from molded plastic and which body 1 may have any predetermined length with such being determined by the average distance between the chin and crotch of babies of varying ages. Thus, the same may be produced in varying lengths so as to accommodate babies of different heights. Said body 1 is transversely arcuated in a concavo-convex manner so as to present a depression or cavity 2 for receiving the front portion of the baby's body, that is, the chest and abdominal portions with such body portion 1 being of sufficient transverse extent so as to provide limited, but requisite, lateral support as in the regions indicated at 3 for assuring of proper retention of the baby within the said cavity 2. Also, said body portion 1 is longitudinally arcuated in a concavo-convex manner with the concave face being coincident with the transverse curvature so as to present a suitable protrusion as at 4 for accommodating the baby's stomach. Said body portion 1, at one of its ends, is convergingly tapered on both of its side margins, as at 5, 5', for providing an extension 6 receivably between the upper portions of the baby's legs for presentation against the groin and crotch. At its end remote from extension 6, body portion 1 converges slightly along its side margins, as at 7, 7', to provide suitable clearance for the baby's arms and with said converging side portions 7, 7' terminating along an edge 8 which is continuous with the inner end of a co-extensive flange-like projection 9 for providing a chin rest which, for purposes of comfort, may be slightly concave.

With reference being particularly made to FIGURE 1, it will be seen that in use the normally inner or concave face of body portion 1 is presented against the front of the baby's body with extension 6 presented between the upper leg portions and with edge 8 being disposed against the upper front portion of the baby's neck so that the chin will be presented against rest 9. By the unique contouring of device A, the baby is snugly and reliably received within body portion 1 which, through its inherent rigidity, provides a stable support surface for easy maintenance of the baby in selected position, such as vertically. Regardless of the size of the attendant's hand, suitable force will be provided for retaining device A in engaged position. Thus, the user is certain that the baby is properly supported and maintained so that the attendant's other hand may be used for tapping or patting the baby on the exposed back to assist upward escape of any air that might have been entrained during fluid feeding. The baby's head is properly supported against any inadvertent injury through jarring and additionally the said device will be

a source of comfort to the child during the eructating process as offering a sensation of security.

It will be seen that with device A against the baby, the same will create pressure as by holding the child thereagainst so that the same will aid in the expulsion of any air accumulated in the stomach.

It should be understood that changes and modifications in the formation, construction, and arrangement and combination of the several parts of the device for aiding in eructation of babies may be made and substituted for these herein shown and described without departing from the nature and principle of my invention.

Having thus described my invention, what I claim and desire to obtain by Letters Patent is:

1. A device for aiding in the eructation of babies comprising a body portion being transversely arcuated to assume a concavo-convex configuration for disposition against the chest and abdominal portions of a baby, said body having side portions for disposition against the sides of the baby and convergingly tapering end portions, a chin support formed integral with said body at one end

portion, and a crotch extension at the other end portion for reception between the upper leg portions of the baby.

2. A device as defined in claim 1 and further characterized by said body having a longitudinally extending arcuation for presenting a protuberance for accommodating the baby's stomach.

3. A device as defined in claim 2 and further characterized by being fabricated of molded plastic.
